APPARATUS FOR CLAMPING MOLDS IN THE
CENTRIFUGAL CASTING OF PIPE AND THE
LIKEJohn J. Nolan, Jr., New York, N. Y., assignor to
The Central Foundry Company, New York,
N. Y., a corporation of Maine

Application October 12, 1946, Serial No. 703,023

1 Claim. (Cl. 22—65)

1

The invention relates to the centrifugal casting of pipe and similar articles.

In my prior patent, No. 2,378,723, granted June 19, 1945, I have disclosed an improved method of making cast iron pipe in uninsulated permanent molds, such as a two-part iron mold. The present invention relates to improvements in the construction and operation of the two-part molds which are particularly useful in the practice of that method, and which are also useful in the centrifugal casting of iron pipe by other methods known to the art.

In the practice of the method described in my prior patent aforesaid, a type of mold is selected which permits rapid removal of the casting so that such removal can be effected at the very moment that the casting has solidified sufficiently to hold its form. One of the features of my present invention is the provision of improvements in the known types of two-part molds which facilitate rapid removal of the casting and thus increase their usefulness in the practice of the method referred to.

Two-part molds for centrifugal casting have been proposed heretofore. I have found, however, that the use of such molds leads to serious practical difficulties from the standpoint of maintaining an effective seal between the mold parts under the conditions encountered at high speeds of rotation. It will be appreciated that with speeds as high as 600 to 800 R. P. M., in pouring, for example, a 70 pound pipe, enormous centrifugal forces are created. To the weight of the cast metal there is added the weight of the mold itself, the two halves of which, parted on a plane which contains or lies adjacent the axis of rotation, are urged apart with tremendous force tending to overcome the restraining influence of whatever means are employed to secure them together. It has been a leading object of this invention to provide improvements in the construction and operation of two-part molds which make it possible to maintain an effective seal at the parting line even under the adverse conditions mentioned.

A specific object of the invention is to provide an improved method of securing together the two halves of a mold for centrifugal casting. Other objects and advantages will appear as the description proceeds.

The drawings illustrate a preferred form of my improved casting apparatus.

Fig. 1 is a side elevational view of the general arrangement.

Fig. 2 is a detail view of one of the hydraulic

2

cylinder mold clamping mechanisms employed in the practice of my invention, this mechanism being shown in locked position with the mold halves fully closed.

Figs. 3 and 4 are detail views partly in cross-section illustrating one form of double check valve or coupling which can be used as means for connecting the hydraulic cylinder of the mold clamping mechanism to a source of fluid pressure and for locking the fluid in the cylinder under pressure.

Figs. 5 and 6 show the construction and operation of the mold and mold securing means, the mold being shown in cross-section and the mold securing means being shown partly in cross-section and partly in elevation. Fig. 5 (taken as indicated at 5—5 in Fig. 2) shows the mold halves clamped together and Fig. 6 illustrates the last part of the mold securing operation or the first part of the mold releasing operation.

While the invention relates to the construction and operation of two-part molds and therefore is not directly concerned with the means for mounting and rotating the mold, it is believed that the invention will be more fully understood when described in its relation to one form of complete casting machine to which it is applicable. Hence I have shown a general arrangement of such a machine in Fig. 1. I wish it to be clearly understood, however, that the invention is applicable to other forms of casting machines. Here we have a mold for the centrifugal casting of pipe or the like which is suitably mounted for rotation about a substantially horizontal axis. Suitably mounted on the bed 1 of the machine are bearing supports 2 for a shaft 3 to which are fixed a pair of flanged rollers 4 which, in conjunction with a second pair of rollers 4 similarly mounted on a shaft at the other side of the machine (not shown), are designed to support and rotate the mold 5 by their engagement with the flanges 6 thereof. One or both of the roller shafts are driven from a suitable power source such as the motor 7.

As is the universal practice in the pipe casting art, the mold is open at the end to receive the metal which is to be cast. Suitable means for introducing the molten metal are provided, such as the pouring trough 8 which may be mounted on a carriage 9 for movement toward and away from the mold. In the particular form of apparatus shown, the movement of the carriage is accomplished by means of a crank 10, mounted on a support 11 at the end of the ma-

chine, through a system of pulleys and the driving cables 12 and 13.

The mold comprises a cope half 14 and a drag half 15 secured together by a series of clamping bands 16 and hydraulic cylinder mold clamping mechanism indicated generally at 20.

The ends of the mold, or either of them, may be provided with hubs 17 for forming, with or without the use of suitable cores, bells, flanges or other pipe end fittings. In this connection it should be observed that one of the important advantages of employing a two-part mold as opposed to a unitary mold from which the pipe is withdrawn endwise, is that such fittings can be formed on both ends of the pipe section. In practical operation, however, the use of two-part molds for centrifugal casting poses a serious problem in securing the mold halves together in such a way as to withstand the enormous centrifugal forces to which they are subjected and at the same time maintain an effective seal at the mold parting. It is to this problem that my invention is directed principally.

In accordance with my invention, the mold halves 14 and 15 are surrounded by steel bands comprising the band segments 18 and 19, and force is applied to the band segments by fluid pressure means (indicated generally at 20, Figs. 1 and 2) to close the mold halves tightly together. In the construction illustrated, the mold halves 14, 15 are hingedly connected at one side as by means of pins 21 passing through overlapping portions of the band segments 18, 19. The band segments 19 are fixed to the drag half 15 of the mold in any suitable manner, for example, by welding. The band segments 18 may be secured in a similar manner to the cope half of the mold but I prefer that the cope half be left free so that it can be lifted off when the band segments 18 are swung open.

In my preferred construction the band segments 18 and 19 are arranged in pairs as shown in Figs. 1 and 2. Each pair of segments 18 are joined by an arcuate plate or web 22 which preferably is shorter than the band segments as seen best in Figs. 5 and 6. Similarly, an arcuate plate or web 23 extends between the band segments 19. The band segments 19 are welded or otherwise secured to the drag half 15 of the mold through the plate or web 23. The clearances 24, 25 provided between the bands 18 and 19 and the mold halves at points beyond the ends of the plates 22 and 23 make it possible to utilize the springiness of the steel bands to advantage in maintaining high clamping pressure against the mold halves once they have been locked together in the manner which I shall describe more fully below.

The locking ends of the band segments 18 and 19 are arranged to lie adjacent one another when the mold is closed. The locking ends of band segments 19 preferably are connected by a plate 27 welded or otherwise secured thereto. The hydraulic cylinder 26 of each clamping mechanism is fixed between the bands 19 in a position to bear against the plate 27 as best illustrated in Figs. 5 and 6. In practice these cylinders usually are welded in place although this is not essential and other securing means may be employed as desired. The piston rod 28, connected to piston 29 operating in the cylinder, is secured at its other end to a pin 30 which, in the construction shown, passes through an aperture 31 formed in a transverse member 32 fixed to the piston rod. Transverse member 32 is of such a length as to fit be-

tween the pair of bands 19. The pin 30 extends through a pair of slots 33 in the bands 19, these slots extending in line with the cylinder 26. Pivotally mounted on the ends of pins 30 is a yoke 34 arranged for engagement with a pair of notches 35 formed in the ends of band segments 18.

When the piston 29 is in the retracted position shown in Fig. 6 with the mold halves closed as shown in that view, the yoke 34 can be swung 10 freely into and out of position for engagement with the notches 35 as will be understood by comparing the full line and dotted line positions of the yoke. As the piston advances in the cylinder, the yoke moves into the position shown in Fig. 5, 15 engaging the notches 35 and thus clamping the mold halves tightly together.

The cylinders 26 are connected to a fluid conduit 36 having a valve 37 arranged to lock fluid in the cylinders under pressure. I have discovered 20 that with this arrangement, upon feeding molten metal into the mold and rotating the mold, the heat of the metal distributed over the inside surface of the mold raises the temperature of the fluid locked in the cylinders and produces 25 an increase in pressure, causing the mold halves to be clamped more tightly together as the mold is rotated during casting.

The yokes 34 of the clamping mechanism can be quickly released by opening the valve 37 and 30 withdrawing the fluid. In my preferred construction the cylinders 26 are connected to a second fluid conduit 38 which, through a valve 39, 35 may be placed in communication with a source of fluid pressure for speedy and positive retraction of the pistons 29 to unclamp the mold.

The conduit pipes 36, 38 may be assembled in sections extending between the cylinders, the latter being formed with connecting passageways 40, 41 to which the pipe sections are attached as by 40 screw-threaded engagement. Passageways 40, 41 are in communication with the respective ends of the cylinder providing communication therewith at the opposite sides of the piston as clearly shown in Figs. 5 and 6.

45 In my preferred construction the fluid conduits are arranged for connection to a pump or other source of fluid pressure (not shown) by inlet and outlet pipes 42, 43 through a four-way valve indicated somewhat diagrammatically at 44 (Fig. 1).

Valves 37 and 39 may be of any suitable construction, and to illustrate my preferred embodiment I have shown in Figs. 3 and 4 a conventional type of self-sealing coupling which is well suited 50 for this use. Couplings of this type permit ready attachment and detachment, and the action of coupling or uncoupling automatically unlocks or locks the ends of the two conduits as the case may be. As valves of this type are well known 55 and have been on the market for a great many years, it will be unnecessary to explain their construction and operation in detail here. Suffice it to say that there is a pair of check valves 46, 47 arranged to seal the ends of the respective coupling members 48, 50 by closing the apertures 51, 52 thereof, these check valves being pressed into locked or sealing position by the coil springs 53, 54 when the coupling is taken apart as shown in Fig. 4. When the coupling is put together as 60 shown in Fig. 3, the check valves 46 and 47 are pressed away from their sealing positions by engagement with the ends of the opposing coupling members, opening a fluid passage through the coupling.

65 The mold halves 14 and 15 provided a cylindri-

cal mold cavity 55 and have flat meeting faces 56, 57, respectively, adjoining the mold cavity at the parting line, and complementary inclined portions 58, 59 adjacent the outer portion of the flat meeting faces arranged to be wedged together when the mold halves are closed tightly. With particular reference to Fig. 5, it will be observed that when the mold halves are closed tightly, the flat faces 56 and 57 and the inclined surfaces 58 and 59 are in contact, but a clearance is provided at 60. I have found that a much more effective seal can be obtained when this clearance is provided so that the molds are in tight contact along the flat faces 56 and 57 and also along the inclined wedged surfaces 58, 59 with clearance provided at other points.

The mold halves 14 and 15 preferably are also provided with complementary inclined surfaces near the ends of the mold as indicated at 61, 61 in Fig. 1 to give a wedging effect as the mold halves are drawn together.

The mold clamping mechanism 20 can be used at one or both sides of the mold. If at both sides, the construction shown is duplicated at the opposite side, being substituted for the hinged connection 21. Also, the fluid conduits 36 and 38 are duplicated at the opposite side, and the two sets of conduits can be joined together at the end of the mold (right hand end as viewed in Fig. 1) so that a single set of valves 37, 39 serves for the clamping mechanism 20 at both sides of the mold. The band segments 18 can be permanently attached to the cope half 14 of the mold, and the notches 35 are formed in both ends of these band segments. Both ends of band segments 19 are formed in the same way for attachment of the hydraulic cylinders 26, yokes 34 and other associated mechanism I have described.

In the practice of my method, using the form of apparatus specifically described herein, the mold is first assembled for casting by lowering the cope half 14 onto the drag half 15 as with the use of a chain hoist attached to the ends of the cope or to the ends of a bar supporting the same. When the cope is lowered into place, the band segments 18 are in the position shown in dot dash lines in Fig. 6 and the yokes 34 of the clamping mechanism are dropped down out of the way with the piston retracted as shown in Fig. 6. The band segments 18 are then brought into the position shown in full lines in Fig. 6 and the yokes are swung into the position shown in full lines in this same view. With the yokes in this position, couplings 37 and 39 are closed and the four-way valve 44 operated to connect the conduit 36 with the inlet pipe 42 and the conduit 38 with the outlet pipe 43. Water or other liquid under high pressure is thus admitted above the pistons 29 and the liquid below the pistons flows back to the pump as the pistons move from the position shown in Fig. 6 to that shown in Fig. 5 and clamp

the mold halves tightly together. Assuming that the surface of mold cavity 55 has been prepared for casting, molten metal is now fed into the mold and the mold is rotated to distribute the metal over the inside of the mold and raise the temperature of the fluid locked in the hydraulic cylinders 26, whereby an increased pressure is produced within the cylinders, causing the mold halves to be clamped more tightly together as the mold is rotated during casting.

When the mold clamping mechanism is employed at both sides of the mold as I have described previously, exactly the same procedure is followed except that after assembling the mold 15 for casting by lowering the cope half 14 onto the drag half 15, the step of bringing the band segments 18 from the dot-dash position shown in Fig. 6 into the position shown in full lines in that view is eliminated because these band segments are permanently attached to the cope half 14 of the mold. Instead, the yokes 34 of the clamping mechanism at both sides of the mold are swung into the position indicated in full lines in Fig. 6, and the operation is continued as I have described above.

The terms and expressions which I have employed are used in a descriptive and not a limiting sense, and I have no intention of excluding such equivalents of the invention described, or of portions thereof, as fall within the purview of the claim.

I claim:

A multi-part metal centrifugal pipe casting mold having fluid pressure clamping devices 35 mounted in heat conducting relationship with the metal of the mold, and a valve for locking fluid in the clamping devices, said valve being mounted on the mold for rotation therewith and having a detachable connection to a source of fluid pressure, whereby the clamping devices can be disconnected from the pressure source before rotation of the mold and remain disconnected during rotation of the mold.

JOHN J. NOLAN, JR.
